[57] **CLAIM**

The ornamental design for a comfort band for headwear, as shown and described.

DESCRIPTION

FIG. 1 is a front elevational view of the comfort band for headwear showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an isometric view thereof.

The broken line showing of the word Logo in FIG. 1 and the cap in FIG. 7 are for illustrative purposes only and form no part of the claimed design.

FIG. 1

FIG. 2

FIG. 3

FIG. 4

FIG. 5

FIG. 6

FIG. 7
